(57) **CLAIM**

The ornamental design for a food container, as shown and described.

DESCRIPTION

FIG. 1 is a left front perspective view of a contain portion of a food container, showing our new design;

FIG. 2 is a top plan view thereof;

FIG. 3 is a left side elevational view thereof;

FIG. 4 is a bottom plan view thereof;

FIG. 5 is a right side elevational view thereof;

FIG. 6 is a rear side elevational view; and

FIG. 7 is a front side elevational view thereof;

FIG. 8 is a left front perspective exploded view of a food container, showing our new design;

FIG. 9 is a top plan view thereof;

FIG. 10 is a left side elevational view of a lid portion of a food container, showing our new design;

FIG. 11 is a right side elevational view thereof;

FIG. 12 is a front view thereof;

FIG. 13 is a rear view thereof;

FIG. 14 is a bottom right perspective view thereof; and,

FIG. 15 is a top left perspective view thereof.

The broken lines in the drawings depict portions of the food container that form no part of the claimed design.
